ELECTRIC POWER-UNIT FOR FASTENER-
APPLYING DEVICES

Charles E. Shan's and Nathan R. Smith, Los Angeles, Calif., assignors to Boston Wire Stitcher Company, Portland, Maine, a corporation of Maine

Application December 17, 1935, Serial No. 54,860

12 Claims. (CL 1-3)

This invention relates to an electric power-unit for operating fastener-applying devices such as stapling implements for attaching papers and other sheets, for securing tags and labels to articles of commerce, and for use generally in fastening or stapling together various objects and articles.

One of the objects of the invention is to provide a power-unit of the type indicated including an arm or lever actuated by an electromagnet to operate a movable element of the fastener-applying implement.

Another object of the invention is to provide an apparatus of the type indicated which is adapted to detachably mount self-contained and interchangeable fastener-applying implements to be actuated by the power-unit to apply the fasteners.

Another object of the invention is to provide an apparatus of the type indicated in which the motion imparted to the actuator by the magnet is multiplied to operate the staple-applying mechanism through a relatively extended stroke.

Another object of the invention is to provide a compact, light-weight power-unit which is conveniently portable and adapted to be connected to any usual outlet for supplying current for its operation.

Another object of the invention is to provide an apparatus of the type indicated which is of simple structure, positive and efficient in its operation and adapted for use over long periods of time without repair or replacement of its parts.

Further objects of the invention are set forth in the following specification which describes a preferred form of construction of the device, by way of example, as illustrated by the accompanying drawings. In the drawings:

Fig. 1 is a perspective view of the present improved apparatus showing it mounted in operative position on a table and illustrating the relationship of a conventional stapling implement thereto;

Fig. 2 is a longitudinal sectional view of the apparatus shown in Fig. 1 with a part of the enclosing housing removed and showing the power-operated arm in its raised or inoperative position;

Fig. 3 is a view similar to Fig. 2 showing the arm operated by the energized magnet to actuate the depressible element of the fastener-applying implement;

Fig. 4 is a transverse sectional view of the device taken on line 4-4 of Fig. 3 and showing the pivotal mounting of the actuating arm between the stanchions on the supporting base;

Fig. 5 is a transverse sectional view taken on line 5-5 of Fig. 3 and showing the manner of attaching the electromagnet and enclosing housing to the supporting base;

Fig. 6 is a transverse sectional view taken on line 6-6 of Fig. 3 and showing the relationship of the elements of the electromagnet and the actuating arm;

Fig. 7 is a transverse sectional view taken on line 7-7 of Fig. 3 and showing the manner of clamping a self-contained fastener-applying implement in adjusted position on the supporting base of the apparatus; and

Fig. 8 is a diagrammatical view of an electrical circuit for controlling the electromagnet.

The present invention consists in general in providing a power-unit to which a standard type of desk stapler or other self-contained fastener-applying implement may be applied for operation therefrom. The fastener-applying unit is adapted to automatically feed the fasteners which are driven into engagement with the work by the actuation of a depressible element thereon. The depressible element is actuated by an arm on the power-unit mounted for swinging movement about a fixed pivot and extending longitudinally of the unit. The arm carries an armature adjacent its pivot which is operated through a relatively short stroke by an electromagnet. The opposite end of the arm moves through a considerably longer stroke to actuate the depressible element of the fastener-applying unit. The energization of the magnet is controlled by an electric circuit including a circuit-breaker of the push-button type adapted to be operated by an attendant.

In the preferred form of the invention as illustrated in the present drawings the apparatus includes a relatively long and narrow supporting frame or base 9 preferably constructed as an aluminum casting having a horizontal platform 10 and a depending marginal flange 11 surrounding its edge. An upstanding marginal rib 12 extends around the edge of the platform 10, terminating on either side at a point spaced from one end. A cross-rib 13 extends between the opposite sides of the marginal rib 12 to form a forwardly located recess 14 and a rearwardly-positioned recess 15. A plurality of bosses 16 formed on the bottom of the platform 10 carry rubber feet 17 to adapt the base to be positioned on a table, desk, bench or the like without marring its finish. On opposite sides of the base 9 adjacent the ends of the marginal rib 12 are bosses 18 into which threaded studs 19 are screwed or

otherwise secured to project upwardly from the platform 10. Nuts 20 on the studs 19 are adapted to be screwed toward or away from the platform 10 of the base member for a purpose as will 5 later be explained. In the rearward recess 15 are pairs of laterally-spaced vertical stanchions 21 and a pair of laterally-spaced longer stanchions 22 for carrying the parts of the power-operated mechanism to be later described. Suitable 10 holes 23 are provided in the cross-rib 13 through which screws may be passed to permanently attach the base 9 to a table, bench or other support if desired.

The forward portion of the frame or base member 9 is adapted to support a fastener-applying implement, indicated in the drawings by the reference character 25. As herein illustrated the implement 25 is of a form and construction as illustrated and described in an application for 15 U. S. Letters Patent Serial No. 696,353, filed November 2, 1933, but implements of other types may also be applied to the power-unit. Suffice it to state herein that the fastener-applying implement or stapling device comprises a base 26 having a clinching anvil 24 at its forward end; an arm 27 pivoted to the base and forming a magazine for containing a supply of fasteners or staples 28; and a depressible lever 29 on the pivoted arm connected to a driver 30 for applying the fasteners or staples to the work. To apply the stapling device 25 to the power-unit its base 26 is slid inwardly under the nuts 20 carried by the threaded studs 19, the opposite portions of the marginal rib 12 together with the cross-rib 13 acting to guide the base into position on the supporting platform 10. The implement 25 is then clamped in adjusted position by turning down the nuts 20 on the studs 19 which engage the base 26 to clamp it securely to the platform 40 10 as shown in Fig. 7.

The depressible lever 29 of the fastener-applying implement 25 is operated by an arm 32 actuated by an electromagnet in the power-unit. As herein illustrated the arm 32 is pivotally 45 mounted at one end between the laterally-spaced stanchions 22 on the base 10 of the unit. As most clearly shown in Fig. 4, the arm 32 has a bore 33 in axial alignment with bores 34 at the upper ends of the stanchions 22. A pivot pin 35 extends through the bores 33 and 34 with nuts 36 screwed onto its threaded ends, a suitable bushing 37 being provided in the bore 33 surrounding the pin. The arm 32 is normally urged to rock about its pivot 35 to raise its forward end 50 by the tension of a hairpin spring 38. The spring 38 is arranged with its crossbar 39 engaging the underside of the arm 32 and its legs 40 extending across the projecting ends of the pin 35 and bent inwardly to engage the forward sides of the stanchions 22. At the opposite free end of the arm 32 is a button 41 of hard rubber or its equivalent which is positioned directly above the knob 42 on the depressible lever 29 of the fastener-applying unit 25. The button 41 is attached to the arm 32 in any suitable manner as by means of a cap-nut 43 screwed onto a suitable threaded fastener extending through the arm 32, see Fig. 2. Intermediate its ends the arm 32 has an encircling rubber buffer ring 44 60 for limiting its upward movement by engagement with the housing 45 to be later described in detail.

The arm 32 is adapted to be actuated by an electro-magnet 50 carried by the supporting frame 9 and to this end the arm carries an ar-

mature 51. The armature 51 is in the form of a rectangular block of laminated construction with overlying strips of metal rigidly connected by rivets 52. A bore 53 extends through the center of the armature 51 and is countersunk at one end to provide a conical seat 54. A stud 55 extends through the bore 53 in the armature 51 with its conical head 56 engaging the seat 54 and its threaded end screwed through the arm 32 and locked in place by a nut 58. The bore 53 is 10 slightly larger than the shank of the stud 55 to provide a clearance to permit limited rocking movement of the armature 51 longitudinally of the arm 32.

The electromagnet 50 may be of any suitable 15 form to adapt it to attract the armature 51 and, as herein illustrated, it comprises an E-shaped laminated iron core 60 and coil 61 on the centrally-positioned leg of the core. Preferably, the magnet is of the alternating current type having 20 its coil windings so designed that the current flow at the end of the operating stroke of the arm 32 is only one-tenth of its maximum value whereby arcing at or burning of the switch contacts is avoided. As most clearly shown in Fig. 6, the coil 61 is held in position on the core 60 by means of a U-shaped strap 62 embracing the centrally-positioned leg of the core and with its opposite ends 63 bent outwardly over the top 25 of the coil. The magnet 50 is mounted on the supporting frame or base 9 with the outer legs of the core 60 positioned between the laterally-spaced stanchions 21 of each pair. The core 60 is rigidly attached to the stanchions 21 by means 30 of rivets 64 extending through suitable aligned apertures in the outer legs of the core and stanchions. The upper ends of the outer legs of the core 60 have suitable short-circuiting rings 65 set 35 in slots therein and functioning to give a delayed 40 action to the armature 51 and arm 32.

The electromagnet 50 and rearward portion of the actuating arm 32 are enclosed by the housing 45, previously referred to, which is made in two 45 cooperating parts 69 and 70 suitably shaped to enclose the elements. The edges of the walls of the two parts 69 and 70 of the housing abut in a vertical plane centrally of the base 9 and the part 70 has a projecting bead 71 to form a lapped joint. The bottom of the housing 45 rests on the platform 10 within the marginal rib 12 and the separable parts 69 and 70 have inwardly-directed feet 72 which are attached to the platform 10 by means of screws 73 extending through the platform and screwed into tapped holes in the feet, see Fig. 5. Bosses 74 formed integrally with the parts 69 and 70 of the housing project inwardly from its opposite sides to guide the armature 51 for movement in a vertical plane. The housing 45 has a forwardly-positioned aperture 76 through which the arm 32 projects longitudinally of and above the fastener-applying implement 25.

The coil 61 of the magnet 60 is energized from a suitable source of current 80 flowing through 65 an electric circuit including a connector plug 81 and circuit-breaker or switch 82. As shown diagrammatically in Fig. 8, current enters from one side of the line 80 through one contact of the plug 81 and thence flows through the coil 61 of 70 the magnet 60, through the circuit-breaker 82 and then back to the opposite side of the line. In the preferred form of wiring herein illustrated the two conductors are carried by a single cable 83 of usual construction having the plug 81 75

and circuit-breaker 82 at the opposite ends and a looped portion extending into the housing 45 through a suitable opening 84. The looped portion of the cable 83 embraces the stanchion 22 to resist pulling strain applied to the cable. One of the conductors in the looped portion of the cable 83 within the housing is withdrawn and connected in series with the coil 61 while the circuit-breaker 82 is connected across the conductors at the end of the cable. As herein shown the circuit-breaker or switch 82 is enclosed in a compressible actuator 85 of soft rubber adapted to rest on the floor and to be depressed by the foot of an attendant to close the circuit. The invention having now been described as embodied in a preferred form of construction its mode of operation will next be explained.

The frame or base 9 is mounted on a table, bench or other support on which it is to be used and may be permanently attached thereto by screws or the like extending through the holes 23 in the base. The fastener-applying implement 25 is then placed on the base 9 and adjusted so that the knob 42 of the depressible lever 29 is positioned directly below the rubber button 41 at the end of the arm 32. The implement 25 is clamped in adjusted position by turning down the nuts 20 on the threaded studs 19 until they engage the beveled side portions of the base 26 to rigidly clamp it on the platform 10. The parts of the apparatus are then positioned as shown in Fig. 2 with the spring 38 acting on the arm 32 to raise the latter to engage the rubber ring 44 with the housing 45. The connector plug 81 is inserted in a suitable electrical outlet to connect the circuit of the apparatus with the source of current as indicated in Fig. 8. The compressible switch-actuator 85 carrying the circuit-breaker 82 is placed on the floor adjacent to the table in position to be actuated by the attendant and the apparatus is ready for use.

The attendant places the work to be stapled, indicated by the reference character *w* in Fig. 2, on the base 26 beneath the pivoted arm 27 of the fastener-applying implement 25. The implement 25 is so constructed as to automatically advance the staples 28 or other fasteners to a position beneath the driver 30 which applies them to the work in the usual manner. To operate the stapling device the attendant depresses the actuator 85 to close the circuit at the switch 82. When the circuit is thus closed current from one side of the line flows through the windings of the magnetic coil 61, thence through the circuit-breaker 82 and through the plug 81 to the opposite side of the line. The coil 61 will consequently be energized to set up a strong magnetic field which attracts the armature 51 with considerable force to swing the arm 32 downwardly from the position shown in Fig. 2 to that shown in Fig. 3 against the action of the spring 38. The armature 51 is guided in its movement by the inwardly-projecting bosses 74 on the housing 45 and because of its loose mounting on the arm 32 is permitted a limited longitudinal rocking movement to compensate for the angular relation of the arm with respect to the ends of the core 60 disposed opposite the armature.

During the downward movement of the arm 32 the button 41 at its outer end engages the knob 42 on the depressible element 29 of the stapling device 25 to apply a staple to the work *w*, the legs of the staple being clinched against the underside of the work by the anvil 24. The armature 51 is located adjacent its pivot 35 on the

arm 32 and consequently it moves through a relatively short stroke, thus acting to actuate the arm with a maximum force. The free end of the arm being located a considerable distance away from the pivot is moved through a relatively long stroke to actuate the fastener-applying implement 25. The arrangement of the magnet 50 and armature 51 permits a variable stroke of the actuating arm 32 and the forward portion of the arm is reduced in thickness to adapt it to yield to compensate for different thicknesses of the work being operated upon.

After each operation of the implement 25 the operator releases the pressure on the actuator 85 of the circuit-breaker 82 to open the circuit and deenergizes the coil 61 of the magnet. The hairpin spring 38 then acts between the stanchions 22 and the arm 32 to rock the latter on its pivot 35 to raise its forward end. The lever 29 and pivoted arm 27 of the fastener-applying implement 25 will then be raised to the position shown in Fig. 2 during which movement another fastener or staple 28 is automatically fed to a position beneath the staple-driver 30. The attendant continues to operate the device to apply fasteners in the manner as above explained, the operation being performed at a high rate of speed limited only by the operator's adeptness in feeding the work to and removing it from the machine. It will be understood that two or more of the units may be arranged adjacent each other and operated in unison by a common switch to simultaneously apply a plurality of fasteners to the work; or the frame 9 may be arranged to detachably mount a plurality of the fastener-applying implements 25 to be actuated simultaneously by the power-operated unit. The implements 25 may also be adapted for lateral adjustment on the base of the unit to vary the spacing between the fasteners applied thereby.

The apparatus and its mode of operation having now been described it will be observed that the present invention provides an extremely simple and compact power-unit for operating fastener-applying implements at high speed with a minimum of effort on the part of the operator to avoid fatigue, while increasing the efficiency of the implement to which it is applied.

While we have herein shown and described one preferred embodiment of the apparatus it is to be understood that various modifications may be made in the structure and arrangement of its parts without departing from the spirit or scope of the invention. For example, the stapling mechanism may be permanently built into the supporting frame of the unit or other forms of self-contained fastener-applying implements may be substituted for that shown. Therefore, without limiting ourselves in this respect, we claim:

1. In an apparatus of the type indicated, the combination of a support, a self-contained fastener-applying implement detachably mounted on the support, said implement having a depressible element for actuating it to apply the fasteners, an arm having one end pivoted to the support with its opposite end adapted to actuate the depressible element of the fastener-applying implement, and an electromagnet intermediate the ends of the arm for moving the latter about its pivot to operate the fastener-applying implement.

2. In a self-contained apparatus of the type indicated, the combination of a support, means for detachably mounting interchangeable fasten-

- er-applying implements on the support for adjustment in relation thereto, means for clamping the implement in adjusted position on the support, said implement having a depressible element operative to apply the fasteners to the work, an arm having one end pivoted to the support and its opposite end adapted to actuate the depressible element of the fastener-applying implement when the arm is moved about its pivot, and an electromagnet on the support adjacent the pivoted end of the arm for operating the latter whereby the actuating end of the arm is given a relatively long stroke with respect to that portion of the arm attracted by the magnet.
15. 3. In an apparatus of the type indicated, the combination of a support, a fastener-applying implement on the support, an arm having one end pivoted to the support and its opposite end adapted to actuate the fastener-applying implement, an armature carried by the arm adjacent its pivoted end, and an electromagnet on the support for attracting the armature to rock the arm about its pivot, said armature having a limited rocking movement longitudinally of the arm to provide for its self-adjustment with respect to the magnet.
4. In a fastener-applying device, a support, means movable on the support for driving fasteners, an arm having one end pivoted to the support with its opposite end adapted to actuate the fastener-driving means, and an electromagnet adjacent the pivoted end of the arm for actuating the latter whereby the arm has a greater range of movement at its free end than at the point of application of the magnetic force.
5. In an apparatus of the type indicated, the combination of a support, a fastener-applying implement detachably mounted on the support, an arm pivotally mounted on the support and adapted to actuate the fastener-applying implement, an electromagnet on the support intermediate the ends of the arm for operating the latter, an electric circuit for energizing the magnet, and a pedally-actuated circuit-breaker for controlling the electric circuit.
6. In an apparatus of the type indicated, the combination of a support having a recess in its base, studs on the base at opposite sides of the recess, a fastener-applying implement mounted in the recess in the base and movable in relation thereto, nuts on the studs for engaging the implement to clamp it in adjusted position on the support, said implement having a depressible element for operating it to apply the fasteners, an arm pivoted to the support for actuating the depressible element of the fastener-applying implement, and a magnet for operating the arm.
7. In an apparatus of the type indicated, the combination of a support, a fastener-applying implement detachably mounted on the support and movable in relation thereto, said fastener-applying implement having a depressible element for operating it to apply the fasteners, means for clamping the implement in adjusted position on the support, spaced stanchions extending upwardly from the support, an arm having one end pivotally mounted between the stanchions with its opposite end adapted to actuate the fastener-applying implement, and an electromagnet between the implement and stanchions for moving the arm about its pivot to actuate the depressible element of the fastener-applying implement.

8. In an apparatus of the type indicated, the combination of a support, a fastener-applying implement detachably mounted on the support, said implement having a depressible element for operating it to apply the fasteners, spaced stanchions on the support, an arm pivoted at one end between the stanchions on the support with its opposite end overlying the fastener-applying implement to adapt it to actuate the depressible element thereof, a spring between the stanchions and arm for holding the arm in inoperative position, and an electromagnet on the support between the stanchions and fastener-applying implement for operating the arm against the action of the spring to actuate the depressible element.

9. In an apparatus of the type indicated, the combination of a support, means on the support for applying fasteners including a depressible element, an arm pivoted to the support and adapted to actuate the depressible element, a magnet on the support having a core and a magnetic coil surrounding the core, an armature carried by the arm, a housing on the support enclosing the magnet, and means on the housing for guiding the armature for movement in a vertical plane.

10. In an apparatus of the type indicated, a supporting base, a fastener-applying implement on the supporting base, an arm pivotally mounted on the base and adapted to actuate the fastener-applying implement, an electromagnet on the supporting base intermediate the ends of the arm, an armature for the magnet, and means for attaching the armature to the arm to provide for its angular adjustment with respect to the arm.

11. In an apparatus of the type indicated, the combination of a supporting base, a fastener-applying implement mounted on the supporting base and movable in relation thereto, means for clamping the implement in adjusted position on the supporting base, an arm pivotally mounted for movement toward and away from the supporting base, an electromagnet for operating the arm, a housing for enclosing the electro-magnet, said housing having an opening through which the arm extends, means on the end of the arm for engaging and actuating the fastener-applying implement, and a resilient collar on the arm within the housing for engaging the walls of the housing to limit the movement of the arm.

12. In an apparatus of the type indicated, the combination of a supporting base, a fastener-applying implement detachably mounted on said base and movable in relation thereto, said implement having a depressible element for operating it to apply the fasteners, means for clamping the implement in adjusted position on the base, stanchions extending upwardly from the base, an arm pivotally mounted at one end between the stanchions with its opposite end adapted to actuate the depressible element, an electromagnet on the base between the fastener-applying implement and stanchions, an external armature carried by the arm for cooperation with the electromagnet, a spring acting between the arm and stanchions to normally move the arm upwardly, an electric circuit for the magnet, and a pedally-operated circuit-breaker for controlling the circuit to energize the magnet and actuate the arm.

CHARLES E. SHANKS.
NATHAN R. SMITH.
